COMBINED PLANTER AND TRELLIS

Guiseppe Marra, 274 Jefferson St.,
Paterson, N.J. 07512

Filed June 6, 1973, Ser. No. 367,550

Term of patent 14 years

Int. Cl. D6—06; D11—02
U.S. Cl. D6—183

FIG. 1 is a perspective view of a combined planter and trellis embodying my new design;

FIG. 2 is a top plan view of FIG. 1;

FIG. 3 is a side elevational view of FIG. 1; and

FIG. 4 is a cross section taken on line 4—4 of FIG. 2.

I claim:

The ornamental design for a combined planter and trellis, as shown.
